INVENTOR:
Henry H. Robinson,
BY *Arthur J. Farnsworth*,
ATTORNEY.

UNITED STATES PATENT OFFICE

HENRY H. ROBINSON, OF LOS ANGELES, CALIFORNIA

PRESSURE BALANCER

Application filed January 27, 1930. Serial No. 423,756.

In this specification, and the accompanying drawings, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to improvements in pressure balancers for orifice fittings and the like, wherein provision is made for withdrawing an orifice plate, or other member, into an auxiliary chamber under pressure, for the purpose of removing it. A device of such nature is illustrated in U. S. Patent No. 1,569,305, granted to Anson Robinson on January 12th, 1926. The construction of that patent has been utilized herein, for the purpose of illustrating the improvement constituting the present invention, and the manner of its application to this general class of constructions.

Fittings of the general class of which the construction shown in said patent is an example, are adapted for use only with moderate pressures, except in the case of the smaller sizes. This is so because there is always an unbalanced pressure upon the operating rod by which the interior parts are manipulated. In modern practice it is desirable to be able to use such devices in connection with very high pressures, up to a thousand pounds per square inch or more. The tendency also is to the use of large size fittings whenever this is feasible. Under the latter conditions, the unbalanced pressure upon the operating rod is inconveniently great, and may be beyond the capacity of one man to handle. For instance, if the operating rod is three-quarters of an inch in diameter, and the working pressure is 1000 lbs., the unbalanced pressure on the rod will be approximately 441 pounds. Obviously such an unbalanced force would prevent a man from conveniently manipulating the rod.

With the above conditions in mind, the salient objects of the present invention in-

clude; first, to provide a simple auxiliary device that is adapted to co-operate with standard forms of fittings of the general class described, to balance the outward thrust upon the operating rod; second, to secure such balancing force by means of the internal pressure in the fitting, so that the outward pressure upon the operating rod may be balanced at all times, irrespective of the actual pressure in the fitting; third, to furnish a device of this nature that may be conveniently applied and disconnected at will, and one which will in no way interfere with the normal and regular procedure for manipulating the operating rod; and fourth, to accomplish the above by means of a very simple, dependable, and relatively inexpensive construction.

My objects are attained in the manner illustrated in the accompanying drawings, in which:—

Figure 1 is an end elevation of a typical form of an orifice fitting, of the general class described, to which my improved balancer has been applied, certain portions of the construction having been shown broken away for the purpose of disclosing the internal parts;

Figure 2 is a plan view of the above construction; and,

Figure 3 is a side elevation of said fitting, and of my balancer applied thereto, in central section.

Similar reference numerals refer to similar parts throughout the several views.

In the drawings I have illustrated the body member of a standard orifice fitting at 5. This fitting has a bore 6 therethrough, a removable orifice plate 7 intersecting the bore, an auxiliary chamber 8 into which the orifice plate may be withdrawn for removal; and a slotted plug-cock 9, intermediate the bore and chamber. The orifice plate is manipulated by means of an operating rod 10 which enters the chamber through a stuffing box 11, and is adapted to screw into a tapped hole in the upper edge of the plate. The operating rod and plate are adapted to pass through a slot 12 in the plug-cock, and, after they are withdrawn therethrough, the plug-cock may be turned to its closed position to shut off communication between chamber 8 and bore 100.

6. The bonnet 13 may then be removed to permit complete withdrawal of the orifice plate. The insertion of a new orifice plate is made by a reversed series of operations, in a manner that will be obvious.

5 In operating such a device, the rod 10 has to be moved longitudinally, and also rotated to screw it into the tapped hole of the orifice plate. Hand-grip 14 is provided for conveniently accomplishing these manipulations.

10 Constructions of the class described may be easily handled in small sizes, or in the larger sizes when under moderate pressure. Under heavy pressure, where the operating rod 10 has to be of correspondingly large 15 diameter, the unbalanced pressure tending to push it out through the stuffing box may be so great as to be beyond the capacity of a man to handle.

10 My auxiliary pressure balancer comprises a tube 15, that is open to the atmosphere at the bottom, and that communicates at the top with chamber 8, as through the passages 16 and 17. A balancer rod 18 enters the upper 20 end of tube 15 through a stuffing box 19, and carries a packed piston 20 at its lower end. The upper end of this rod carries a bridging member 21, whereby it may be operatively connected to operating rod 10. This connection may be conveniently made in the manner illustrated in the drawings, wherein the bridging member is shown as having a transversely notched outer end 22, adapted to engage a peripheral groove of hand-grip 14. 25 This engagement may be readily accomplished, since balancing rod 18 may be rotated; and the engagement, when made, may be maintained in some convenient manner, as by the latching-bar 23. In the above described 30 construction, the upward pressure upon the operating rod 10 may be exactly balanced by the downward pressure upon piston 20, providing that the cross-sectional area of rod 10 is made the same as the annular portion of piston 20, upon which pressure is exerted. This will be true irrespective of actual variations of pressure in chamber 8. Therefore an operator may freely manipulate rod 10, without appreciable effort.

35 My pressure balancer may be applied to standard construction in various ways, that will be apparent to those familiar with the design and operation of such devices. In the application illustrated, the upper flange 24 of body member 5 has been extended laterally, as at 25; and upon this extension a flanged fitting 26, carrying stuffing box 19 and tube 15, has been mounted. A downwardly sloping passage 16 has been drilled in flange 24, in a position to establish communication between chamber 8 and passages 17.

40 Having thus fully described my invention, in a manner that will make its construction and operation clear to those familiar with 45 the art involved, I claim:

1. In combination with a fitting that is adapted for withstanding internal fluid pressure; a member comprising a longitudinally slidable stem extending into said fitting from outside thereof, and subject to said pressure in a manner that would tend to expel it; a longitudinally slidable piston that is directly subject to said pressure in a direction opposite the expelling pressure on the stem; a piston rod extending from said piston externally of the fitting; and means connecting the piston rod and stem, externally of the fitting, to constrain them to move alike. 70

2. In combination with a fitting that is adapted for withstanding internal fluid pressure; a member comprising a longitudinally slidable stem extending into said fitting from outside thereof; and subject to said pressure in a manner that would tend to expel it; a longitudinally slidable piston that is directly 75 subject to said pressure in a direction opposite to the expelling pressure on the stem; a rod extending from said piston parallel to said stem externally of the fitting; and a swingable bridge separably connecting the piston rod and stem, externally of the fitting, to constrain them to move alike. 80

HENRY H. ROBINSON.
